UNITED STATES PATENT OFFICE.

ALBERT ISIDORE FROMAGER AND JOSEPH FERDINAND SIX, OF MONTREAL, QUEBEC,
CANADA.

SWITCH-BLOCK AND CASING.

1,193,253.

Specification of Letters Patent.

Patented Aug. 1, 1916.

Application filed May 14, 1915. Serial No. 28,197.

To all whom it may concern:

Be it known that we, ALBERT ISIDORE FRO-
MAGER, a subject of the King of Great Brit-
ain, residing at No. 8 Laval avenue, Mon-
treal, Province of Quebec, Canada, and
JOSEPH FERDINAND SIX, a subject of the
King of Great Britain, residing at No. 448^a
Joliette street, Montreal, Province of Que-
bec, Canada, have invented certain new and
useful Improvements in Switch-Blocks and
Casings; and we do hereby declare that the
following is a full, clear, and exact descrip-
tion of the invention, such as will enable
others skilled in the art to which it apper-
tains to make and use the same.

The invention to be hereinafter described
relates to switch blocks and casings.

In order to more clearly disclose the con-
struction, operation, and use of the inven-
tion, reference should be had to the accom-
panying drawings forming part of the pres-
ent application.

Throughout the several figures of the
drawings like reference characters designate
the same parts.

In the drawings: Figure 1 is a top plan
view of the block with the casing removed,
partly broken away; Fig. 2 is a side view
of the same partly in section; Fig. 3 is a
fragmentary underneath view of the block
with the casing removed; Fig. 4 is a section
on line 4—4 of Fig. 2 looking in the direc-
tion of the arrows; Fig. 5 is a top plan view
of the casing and block; and Fig. 6 is a sec-
tion on line 6—6 of Fig. 5 looking in the
direction of the arrow.

The main objects of the invention are to
provide a compact and efficient switch block
for electric circuits and a casing for the
same which coöperate so as to effectually
prevent stealing of the electric current by
shunting it from the main line around the
meter to the house circuit, and which will
permit ready access to the switch block for
the insertion of new fuse plugs.

The block 1 of approximately rectangular
shape, of porcelain or other suitable insu-
lating material, is provided along each side
with a deep groove 2. A copper sleeve 3 is
mounted in each groove 2, near the upper
end thereof, and tightly threaded into the
outer ring 4^a of a copper strip 4. A brass
contact screw 5 is passed through the inner
end of strap 4 and provided with the usual
nut which is held in tight engagement with

the strip so as to establish a close connec-
tion between the same and the screw 5. The
head of screw 5 is flat and is centrally lo-
cated in the bottom of a fuse socket formed
in the face of the block, as is usual.

A rod 7 of copper, or other suitable ma-
terial, having a tapered inner end, is slid-
ably mounted through each sleeve 3 and the
outer ends of these rods are bent inwardly
at right angles and secured to a common
beam 8 of non-conductive material the upper
ends of the rods and the securing nuts there-
for being covered by a casing or shell 9 of
suitable insulating material. The rods 7 are
made a close fit over the sleeves 3 so as to be
in close frictional contact with the interiors
thereof.

A copper tube 10 of the same interior
diameter as the sleeves 3, and in alignment
therewith, is secured in the lower end of each
groove 2. A binding screw 11 is threaded
through block 1 into each tube 10 and en-
gages one of the wires 12 of the main circuit
so as to hold the same in close engagement
with the tube. The tubes are so spaced, rel-
atively to the sleeves 3, that, when the rods
7 are forced inwardly their greatest dis-
tance the inner ends fit snugly into the inner
ends of the tubes 10 and thus establish elec-
trical connection between the main line wires
and the copper strips 4.

In the upper face of block 1, at the cen-
tral portion thereof, there are two parallel
grooves 13 extending from the centers of
the fuse plug sockets to the bottom or end
of the block. In the upper end of each
groove 13 there is a short copper sleeve 14
the upper end of which is threaded into a
thread band 15 through which is threaded
the usual thread collar 16 of the fuse plug
socket, the band also being set in the block
in the usual manner. The switch plug 17
is threaded into the collar 16 until its lower
center contact engages the head of screw 5,
in the usual manner. A block 18 of brass,
or other suitable material, is threaded on
the outer end of each sleeve 14 and secured
on a recess in the block by means of a short
anchor screw threaded into the under face
thereof from the back of the block.

A tube 19 is secured in the outer end of
each groove 13, by means of a block 20
threaded on the inner end thereof similar to
block 18. A rectangular copper plate 21 is
secured on the outer end of each tube 19

and is electrically connected to one wire 22 of the house circuit. Close fitting rods 23 similar to rods 7 are slidably mounted in tubes 19 and have their outer ends connected by a beam 24 similar to beam 8. By forcing beam 8 inwardly so as to bring rods 7 into contact with sleeves 10, and forcing beam 24 inwardly so as to bring rods 19 into contact with sleeves 14, the main and the house circuits are completed in the usual manner.

The block 1 is inclosed in a steel casing 25 from which it is suitably insulated. An integral rib 26 is provided along each side 15 of the casing, near the top thereof. These ribs form, with the top, U grooves in which are slidably mounted steel panels 27 and 28. The upper panel 27 is secured to the beam 8 and is provided with a grip knob 29 operative 20 in short slots 30 in the top of the casing adjacent an opening 31 above the fuse plugs 17, which is provided to permit renewal of the fuses when the same have been burned out. The knob 29 is so located on 25 plate 27 that both of the slots 30 will be completely closed before the rods 7 enter sleeves 10. This eliminates any danger of fire from sparking. Plate 28 is secured to beam 24 so that, when this plate is forced 30 inwardly by means of knob 32 operated in a slot 33 through the top of the casing, the house circuit is closed.

A partition 34 is provided across the casing, at the outer ends of sleeves 14, and 35 completely closes the upper part of the same. By this means the connections of the line and house wires are secured against being tampered with, while access to the fuse plugs is permitted. This effectually prevents the 40 current being carried from the line wire around the meter, as it is impossible to connect to the line wire without being detached. The line wires and the house circuit wires are protected, where they pass 45 through the casing 25, by suitable tubes 35.

It is thought that the construction, operation, and use of the invention will be clear from the preceding detailed description.

Changes may be made in the construction, arrangement, and disposition of the 50 several parts of the invention, within the limits of the claims, without in any way departing from the field and scope of the 55 same, and it is meant to include all such

within this application wherein only a preferred form has been disclosed.

Having thus fully described our invention, what we claim as new and desire to secure by Letters Patent is:

In a device of the character described; a closed casing provided with an opening through its top and slots communicating therewith, near one end, and a slot near the other end, and a transverse partition at its 60 approximate center; a block of insulating material mounted therein and insulated therefrom, said block being provided with grooves and fuse plug sockets in its upper 65 face and grooves in its sides; threaded collars secured in the upper ends of the said 70 plug sockets; sleeves secured in the inner ends of the grooves in the upper face of the said block and electrically connected to the said threaded collar; tubes secured in the 75 outer end of the said grooves in alignment with the said sleeves and adapted to be connected to the opposite sides of an electric circuit; conducting rods slidably operative 80 therein to make contact with the sleeves in the inner ends of the grooves; a beam of insulating material connecting the said rods at their outer ends; a slidably operative plate 85 secured thereto and adapted to be operated from without the casing; a tube mounted in 90 one end of each of the said side grooves of the block and adapted to be connected to one side of an electric circuit; sleeves mounted near the other end of the said grooves in alignment with the said tubes; copper strips 95 connected to the said sleeves at their outer ends; contact screws secured through the inner ends thereof and having their heads centrally located in the bottoms of the said fuse plug sockets; conducting rods slidably operative 100 through said sleeves to make contact with said tubes; a beam of insulating material secured to the outer ends of said rods; and a plate slidably operative within the casing and secured to the said beam, the said plate being adapted to be operated from without the said casing.

In witness whereof we have hereunto set our hands in the presence of two witnesses.

ALBERT ISIDORE FROMAGER.
JOSEPH FERDINAND SIX.
